UNITED STATES PATENT OFFICE.

BENJAMIN H. SMITH, OF WILKINSBURG, PENNSYLVANIA, ASSIGNOR TO WESTINGHOUSE ELECTRIC & MANUFACTURING COMPANY, A CORPORATION OF PENNSYLVANIA.

THERMAL RELAY.

Application filed February 26, 1921. Serial No. 448,104.

My invention relates to relays and particularly to thermal relays.

One object of my invention is to provide a thermal relay that shall have a long time element in its operation.

Another object of my invention is to provide a relay of the above indicated character, for protecting electrical apparatus and that shall reproduce substantially the temperature conditions obtaining in the apparatus.

A further object of my invention is to provide a relay of the above indicated character that shall be simple and economical in its construction and reliable in its operation.

In practicing my invention, I provide two spirally-wound bimetallic members that are mounted on a movable shaft. The inner ends of the bimetallic members are electrically connected through a sleeve of conducting material that is securely mounted on the shaft and insulated therefrom. The outer ends of the bimetallic members are secured to stationary terminals that are disposed on an enclosing casing. The bimetallic members are traversed by the circuit current, and, when heated, turn the shaft upon which they are mounted to effect engagement between two contact members. The bimetallic members are immersed in oil or some similar fluid having a large heat capacity. The combination of the fluid and the bimetallic member so increases the thermal storage capacity of the relay as to reproduce substantially the temperature conditions in the electrical apparatus that is to be protected.

Figure 1 of the accompanying drawings is a front view, partially in elevation and partially in section, of a thermal relay embodying my invention.

Fig. 2 is a side view, partially in elevation and partially in section, with parts broken away, of the relay shown in Fig. 1.

Fig. 3 is a plan view of the relay taken along the line III-III of Fig. 1 and illustrates the contact-adjusting member.

Fig. 4 is a plan view of the adjustable contact-supporting member of the relay shown in Fig. 1.

Fig. 5 is a plan view of the movable contact-supporting member.

Fig. 6 is a front elevational view of the scale of the relay, illustrating the co-opera-

tion therewith of the indicators of the contact members.

Fig. 7 is a side elevational view of the dial and the indicators illustrated in Fig. 6; and

Fig. 8 is a diagrammatic view of an electrical circuit, illustrating the connections thereto of the relay embodying my invention.

Referring to Figs. 1 and 2, the device embodying my invention, comprises, in general, a supporting base 10, a relay 11 supported thereon and a cover 12 that co-operates with the base 10 to enclose the relay 11. The base 10 is provided with two supporting brackets 13 and 14, each of which is provided with a threaded rod 15 that extends outward from the front of the relay and co-operates with a thumb screw 16 to hold the cover 12 in position. Threaded portions 17 that extend from the rear of the base 10 co-operate with a switch board or some similar supporting device to support the relay in any desired position.

The relay 11 comprises a fluid-containing receptacle 20 that is mounted on, and supported by, a supporting member 21 which is secured to the base 10. Supported within the receptacle, between two bearings 22 and 23, is a shaft 24 upon which is disposed a tube 25 of insulating material. Upon the tube 25 is securely mounted a sleeve 26 of conducting material.

Two spirally-wound bimetallic members 27 and 28 are supported by the conducting sleeve 26 and have their inner ends secured thereto, being thus electrically connected to each other. The outer ends of the members 27 and 28 are respectively connected to two terminal members 29 and 30. The terminal members 29 and 30 are connected by flexible conductors to terminal members 31 and 32, whereby the bimetallic members 27 and 28 of the relay may be connected in circuit with the external conductors of the main circuit which is to be protected.

A spirally-wound spring 33 is disposed around the insulating tube 25 and has the inner end thereof secured to the tube and the outer end secured to the fluid-containing receptacle 20. Also mounted upon the shaft of the insulating tube 25 is a contact member 34, the movement of which, with the shaft 24, is controlled by the expansion or contraction of the members 27 and 28. The spring

33 serves as a conducting means to connect the contact member 34 to an external control circuit, as illustrated in the diagram of Fig. 8.

5 In the path of the movable contact member 34 is an adjustable contact member 35 that is adapted to be engaged thereby. The contact member 35 is secured between one pole of a circular permanent magnet 36 and 10 a supporting disc 37 of micarta, as illustrated in Fig. 4. The disc 37 of micarta is disposed on, and supported by, the spindle 38 of the member serving as the bearing 22.

The contact members 34 and 35 are 15 disposed on supporting members 39 and 40 of magnetizable material, and the engagement of the contact members is, therefore, effectively maintained. The disengagement of the contact members is effected with a snap 20 action by reason of the force of the tensioned bimetallic members 27 and 28 acting upon the contact member 34 to disengage the same from the contact member 35. The position of the contact member 35 is controlled by the adjusting member 44 which is 25 retained in such position as it may be placed and prevented from moving therefrom, because of jarring or vibration, by means of a flexed spring 45.

30 The contact members 34 and 35 are connected to two terminal members 46 and 47, respectively, to permit convenient connection thereto of the conductors of an external control circuit.

35 The supporting members 39 and 40 of the contact members are provided with pointers 41 and 42, respectively, that co-operate with a stationary scale 43 to indicate, respectively, the position of the movable and of the 40 stationary contact members, as illustrated in Fig. 6. The scale may be calibrated for average value of current or temperature or for percentage of full-load circuit.

The fluid container is provided with a 45 window or opening 48 through which the position of the contact members 34 and 35 may be observed.

The bimetallic members are immersed in oil or some similar fluid having a large heat-50 storage capacity and they thus serve to simulate the heating conditions of an electrical apparatus which is to be protected by the relay. The temperature of the bimetallic members will thus vary substantially in accordance with the temperature of the conductors of the apparatus that is to be protected and such control as may be desired 55 may be obtained by means of a control circuit, the energization of which is controlled by engagement of the contact members.

As illustrated in the diagram shown in Fig. 8, a translating device 50 is adapted to receive energy from the source 51 of electromotive force through the circuit interrupter 52. The circuit current that traverses

the translating device 50 also traverses the bimetallic elements 27 and 28 and, because of the surrounding oil, heats those members substantially in accordance with the heating of the translating device 50. 70 When the temperature of the translating device 50 and, accordingly, the temperature of the relay attains a predetermined value, engagement of the contact members is effected to complete a control circuit for tripping the 75 interrupter.

It will thus be observed that, by immersing in oil or some other such heat-storage fluid, a bimetallic member that is traversed by the same current that traverses the translating device, a thermal relay may be obtained 80 which will closely simulate the temperature conditions obtaining in the translating device.

My invention is not limited to the specific 85 arrangements or details as illustrated, since various modifications may be made therein without departing from the spirit and scope of the invention, as set forth in the appended claims. 90

I claim as my invention:—

1. A thermal relay comprising a movable shaft, a sleeve of conducting material disposed thereon and insulated therefrom, a plurality of spirally-wound bimetallic members disposed on the conducting sleeve, a contact member controlled by the movement of the shaft caused by the metallic members and an oil-containing vessel for enclosing the bimetallic member. 100

2. A thermal relay having a long time element in its operation for protecting an electrical apparatus comprising a plurality of spirally-wound bimetallic members in circuit with the apparatus, a movable shaft, a sleeve of conducting material securely disposed on the shaft but insulated therefrom and having the inner ends of the bimetallic members secured to the sleeve, a contact member controlled by the shaft and an oil-containing vessel for enclosing the bimetallic members and serving to increase the thermal capacity thereof to cause the same to have a heating characteristic substantially in accordance with the heating characteristic of the apparatus to be protected. 110

3. A thermal relay for protecting an electrical apparatus comprising a bimetallic member traversed by the circuit current and immersed in oil to provide an increased heat-storage capacity to cause that member to have a heating characteristic substantially in accordance with the heating characteristic of the apparatus, a movable member controlled by the bimetallic member and a contact member controlled by the movable member. 120

4. A thermal relay comprising a movable shaft, a bearing therefor, a spirally-wound bimetallic member disposed on the shaft, a 130

contact member controlled by the shaft, an adjustable contact member adapted to be engaged by the former contact member, means cooperating with the bearing for adjusting said member, and means for causing the engagement and the disengagement of the contact members to be effected with a snap action.

5. A thermal relay comprising an opaque vessel adapted to contain a fluid having heat-storage qualities, said vessel being provided with an opening serving as a window, transparent means disposed behind said opening and arranged to co-operate with the vessel to preclude the fluid from issuing through the window, a thermally-responsive member disposed in the fluid, a contact member controlled thereby, and an indicating scale disposed behind the window to indicate the 10 position of the contact member.

15

6. A thermal relay comprising a fluid container, bearings disposed in the top and the bottom portions, a shaft disposed between the bearings, a thermal element for 20 controlling the shaft, a contact member to

be controlled by the shaft and means whereby the position of the contact member may be adjusted by the upper bearing from the outside of the container.

7. A thermal relay comprising a fluid 20 container, bearings disposed in the top and the bottom portions, a contact member, means disposed between the bearings and operative to control the contact member and means disposed externally relative to the 35 container and co-operating with one bearing for adjusting the contact member.

8. The combination with a closed casing containing an operating element, of a bearing therefor extending through the casing, 40 a contact member disposed in the casing and controlled by the operating element and means externally disposed relative to the container and cooperating with the bearing to control the adjustment of the contact 45 member.

In testimony whereof, I have hereunto subscribed my name this 15th day of February 1921.

BENJAMIN H. SMITH.
